UNITED STATES PATENT OFFICE

2,162,877

AMUSEMENT DEVICE

Alvin Bisch, Chicago, Ill.

Application February 20, 1937, Serial No. 126,756

10 Claims. (Cl. 272—41)

The present invention relates generally to an amusement device, but more particularly to one of the captive type suspended from an overhead revolving structure and one which is under the control of the one individual operator so that skillful manipulation of the control presents novel thrills and experience to those operating the device.

The primary object of the present invention is to provide a novel improved compact type of amusement device of the revolving captive type which insures safety of operation.

A further object of the invention is to provide a novel and improved amusement device of the captive type and suspended from a revolving structure in which the passenger carrying cab is adapted to swing upwardly and outwardly with respect to the revolving structure, but is incapable of moving forwardly or rearwardly except with the revolving structure.

These and other objects are accomplished by providing a construction and an arrangement of the various parts in the manner hereinafter described and particularly pointed out in the appended claims.

Referring to the drawing:

Fig. 1 is a diagrammatic view as well as a top plan view of the revolving structure showing the manner in which my improved amusement device may be attached thereto;

Fig. 2 is a side elevational view of the passenger carrying device showing the manner in which it is pivotally suspended to the revolving structure;

Fig. 3 is a cross sectional view taken on the lines 3—3 in Fig. 2; and

Fig. 4 is an enlarged detailed view showing the manner in which the bars are pivotally attached to the revolving structure.

The present invention is an improvement over my co-pending application, Serial No. 62,603 filed February 6, 1936.

In illustrating one form of my invention, I have shown the same in connection with the more or less conventional revolving structure diagrammatically illustrated in Fig. 1 of the drawing and generally indicated by the reference character 10. This revolving overhead structure is provided with a plurality of radially projecting arms 11 which are supported on a tower of substantially the same identical construction as is disclosed in my aforesaid mentioned co-pending application. Secured to the outer ends of each of the arms are bearing brackets 12 which are provided with angularly disposed bearing sockets 13. Pivoted in

the aligned bearings 13 of each of the adjacent arms 11 is a shaft or pipe 14. Rigidly secured to the center of the pipe 14 is a right angularly depending pipe or shaft 15. Secured by means of a bracket 17 to the lower end of the pipe is a bar 16. The bracket 17 is secured to the lower end of the pipe or shaft 15 by a pin 18. The bracket 17 is secured to the plate or bars 16 by means of bolts 19. Secured to the outer ends of the bar 16 is a substantially U-shaped pipe 20. Extending through the pipe 20 is a cable 21 which has its opposite ends diverging upwardly as clearly shown in Fig. 2 of the drawing. The upper ends of the cable 21 are attached to ears 22 of opposite sleeves 23. The sleeves 23 are secured to each end of the shaft 14 by means of pins 24. Intermediate portions of the pipe 15 are reinforced or braced by a series of rods or cables 25 and 26 which have their lower ends secured to space brackets 27 and 28 respectively and their upper ends connected to the ears 22 of each of the sleeves 23. The brackets 27 and 28 are rigidly secured to the pipe 15 by means of pins 29 and 30 respectively.

Mounted on the lower portion of the U-shaped pipe 20 and suitably secured thereto is a cab generally indicated by the reference character 31 which is provided with a seat 32 for holding two passengers therein. Loosely mounted on the pipe 15 and resting on the upper surface of the bar 16 is a pipe or sleeve 33. Secured to the sleeve 33 is a rudder 34 which is relatively narrow at the bottom and gradually enlarges towards the top and occupying a plane normally in the vertical center above the cab 31. Projecting laterally in opposite direction from and secured to the lower end of the pipe 33 are horizontal arms 35. Pivotally connected to the outer ends of each of these arms 35 are connecting rods 36. The other end of these connecting rods 36 are pivotally connected to the outer ends of outwardly projecting arms 37 which in turn are secured to a collar 38. The collar 38 is secured to the upper end of a sleeve 39. The sleeve or pipe 39 is loosely mounted on the forward leg of the U-shaped pipe 20 by means of a pin 41. Secured to the lower end of the pipe 39 is a collar 42 which has a rearwardly projecting arm 43. This arm 43 projects in a direction towards the operator in the cab so that the same may be manipulated for adjusting the rudder 34 with respect to the pipe 15.

Summarizing the operation of my improved amusement device, it will be readily seen that as the revolving overhead structure illustrated in Fig. 1 of the drawing is revolved the centrifugal force together with the manipulation of the rudder 34

34 will actuate the cab 31 together with its supporting structure outwardly about the axis of the shaft or pipe 14 in the bearings 13 so as to cause each of the individual passenger carrying cabs to 5 swing outwardly from the revolving structure. Each of the cabs may be deviated from their normal course induced by the centrifugal force by manipulating the arm 43 by the operator so as to raise each individual cab above or depress it below its normal course, affording great thrills to 10 each of the individual operators in the respective cabs. In this connection it will be noted that by rigidly attaching the cab directly to the pipe 15 and in turn rigidly attaching the pipe 15 to 15 the transverse horizontal shaft 14 relative to and fro movement except with the revolving structure is limited to outwardly and inwardly swinging movement and prevents contacting or striking of the adjacent cab during its normal operation.

20 While in the above specification I have described one embodiment which my invention may assume in practice, it will of course be understood that the same is capable of modification and that modification may be made without deviating from the spirit and scope of the invention 25 as expressed in the following claims:

What I claim is my invention and desire to secure by Letters Patent is:

1. An amusement device comprising an overhead revolving structure, a horizontal shaft journaled on the outer end of said structure, a depending pipe secured to said shaft, a passenger carrying cab rigidly secured to the lower end of said pipe, and a rudder pivotally associated with 30 said cab for controlling the direction of travel of said cab.
2. An amusement device comprising an overhead revolving structure, a horizontal shaft journaled on the outer end of said structure, a depending pipe secured to said shaft, a passenger carrying cab secured to the lower end of said pipe, and a rudder pivoted on said pipe above said cab for controlling the direction of travel thereof.
3. An amusement device comprising an overhead revolving structure in the form of radially disposed arms, a horizontal shaft journaled in the outer ends of two adjacent arms, a depending pipe rigidly secured to the center of said shaft, a passenger carrying cab including a U-shaped pipe 35 rigidly secured to the lower end of said depending pipe, a rudder pivoted to the lower end of said depending pipe and located above said cab, and means for manipulating said rudder from said cab.
4. An amusement device comprising an overhead revolving structure in the form of radially disposed arms, a horizontal shaft journaled in the outer ends of two adjacent arms, a depending pipe rigidly secured to the center of said shaft, 40 a passenger carrying cab including a U-shaped pipe rigidly secured to the lower end of said depending pipe, a cable extending through said U-shaped pipe and having its opposite end attached to the opposite ends of said horizontal pipe, and a rudder pivoted to said depending pipe for 45 directing the deviation of said cab.

5. An amusement device comprising an overhead revolving structure in the form of radially disposed arms, a horizontal shaft journaled in the outer ends of two adjacent arms, a depending pipe rigidly secured to the center of said shaft, a passenger carrying cab including a U-shaped pipe rigidly secured to the lower end of said depending pipe, upwardly diverging cables connecting the upper ends of said U-shaped pipe with the outer end of said shaft, a rudder pivoted to said depending pipe between said diverging cables, and control means operable from said cab for diverting the same. 10

6. An amusement device comprising a revolving overhead structure including a plurality of radially projecting arms, horizontal shafts journaled in the outer ends of the adjacent arms, perpendicular pipes secured to and projecting from the centers of said shafts, cross bars secured to the lower ends of said pipes, passenger carrying 15 cabs suspended from said bars, rudders pivoted on said pipes above said bars, and means for controlling said rudders from said cabs.

7. An amusement device comprising a revolving overhead structure including a plurality of radially projecting arms, horizontal shafts journaled in the outer ends of the adjacent arms, perpendicular pipes secured to and projecting from the centers of said shafts, cross bars secured to the lower ends of said pipes, U-shaped 20 pipes secured to said bars, passenger carrying cabs mounted on the lower portions of said U-shaped pipes, downwardly converging cables extending from said shafts and extending through said U-shaped pipes, rudders pivoted to said 25 perpendicular pipes, and means for controlling said rudders from said cabs.

8. An amusement device comprising a revolving overhead structure including a plurality of radially projecting arms, horizontal shafts journaled in the outer ends of the adjacent arms, perpendicular pipes secured to and projecting from the centers of said shafts, cross bars secured to the lower ends of said pipes, U-shaped pipes secured to the lower sides of said bars, passenger 30 carrying cabs mounted on the lower portions of said U-shaped pipes, sleeves loosely mounted on the lower ends of said perpendicular pipes, rudders secured to said sleeves, arms projecting outwardly from the opposite sides of said sleeves, and 35 connections from said arms to said cabs for controlling the position of said rudders.

9. An amusement device comprising a revolving overhead structure, a cab supporting means pivoted to said structure, a passenger cab connected to the free end of said supporting means, and a rudder pivoted on said supporting means and controlled from said cab. 40

10. An amusement device comprising a revolving overhead structure, a cab supporting means pivoted to said structure, a passenger carrying cab connected to the free end of said supporting means, a rudder pivoted on said supporting means above said cab, and means operable from 45 said cab for controlling said rudder.

ALVIN BISCH.
